VACUUM CLEANER

Ernst Faber, Stuttgart, Germany

Application June 23, 1937, Serial No. 149,980
In Germany August 6, 1936

1 Claim. (Cl. 248—26)

This invention relates to an arrangement for silencing vacuum cleaners according to which the motor and fan unit is supported with respect to the casing of the vacuum cleaner without any metallic intermediate piece. The accompanying sectional drawing through the part of a vacuum cleaner casing surrounding the motor and fan unit shows the arrangement according to the invention in one constructional form by way of example, the arrangement being assembled in somewhat the following manner:—

Over the motor and fan unit 1 which is shown diagrammatically as a cylindrical body, a thick rubber ring 5 is first placed, and thereupon a rubber ring 2 of L-shaped cross section is thereupon placed on the circular end edges. From either end caps 3 and 4 are then pushed over the motor and fan unit, the flanges 3', 4' of which caps bear against the thick rubber ring 5 which lies approximately around the middle of the motor and fan unit. Both the flanges 3', 4' and the rubber ring 5 are provided with holes, through which screw bolts 7 are passed. The cap 4 has only a narrow end flange 4'' and for the rest has a large circular opening for the passage of air. The cap 3 has also a narrow end flange 3'' which surrounds an arched end 3''' provided with perforations. On the bolts 7 being at first only lightly tightened the motor and fan unit will come with both ends surrounded by the rubber ring 2 against the end flanges 3'', 4'' of the caps 3, 4.

When the motor and fan unit thus enclosed is introduced into the casing 8 of the vacuum cleaner, the bolts 7 (6 or 8 of which are arranged

around the periphery) are fully tightened up. The other flanges 3' and 4' which are thus brought closer together will then squeeze the thick rubber ring 5, so that the latter will bear against the casing wall 8 on the one hand and against the motor and fan unit 1 on the other hand. The latter is thus held tightly at its middle periphery in the casing 8 and at the same time the two L-shaped rubber rings 2 at the ends of the motor and fan unit are correspondingly compressed, so that the unit is completely, firmly, but yet elastically supported. The end part 8' of the casing is thereupon pushed over the middle part 8 of the casing.

Instead of rubber rings, rings of materials of similar elasticity and having similar silencing property may be used.

I claim:—

A vacuum cleaner comprising in combination a motor and fan unit, cylindrical caps adapted to be placed over the end parts of the motor and fan unit, elastic rings of L-shaped cross-section disposed between the motor and fan unit and the caps at the corners formed by the end surfaces and the cylindrical surfaces of the two parts, at the other ends of the said caps flanges facing one another, a casing surrounding the motor and fan unit and the caps, a thick elastic ring disposed between the said flanges and bolts connecting the said flanges for drawing the flanges towards one another and thereby compressing the thick elastic ring for causing it to bear tightly against the motor and fan unit and against the casing.

ERNST FABER.
